VENDING MACHINE

Monte L. Levin, Roslyn Heights, N.Y.

Application September 29, 1958, Serial No. 52,800 ,

Term of patent 14 years

(Cl. D52—3)

FIG 2

FIG 1

Fig. 1 is a front perspective view of a vending machine, showing my new design;

Fig. 2 is a side elevational view thereof taken from the right of Fig. 1.

The characteristic features of my design for the vending machine disclosed reside in the combined selector button and display panel mounted on the top and upper front of the cabinet as shown.

What is claimed is:

The ornamental design for a vending machine, substantially as shown and described.
